UNITED STATES PATENT OFFICE.

WILLIAM STEPHEN COX GLOVER, OF OXFORD, ENGLAND.

PLUNGER-TYPE MACHINE FOR WASHING, DYEING, OR OTHERWISE TREATING CLOTHES OR OTHER FABRICS WITH LIQUIDS.

Application filed July 29, 1924. Serial No. 728,887.

To all whom it may concern:

Be it known that I, WILLIAM STEPHEN Cox Glover, a British subject, residing at Oxford, county of Oxford, England, have 5 invented certain new and useful Improvements in Plunger-Type Machines for Washing, Dyeing, or Otherwise Treating Clothes or Other Fabrics with Liquids, of which the following is a specification.

10 This invention relates to improvements in apparatus of the plunger type, for washing, dyeing or otherwise treating clothes or other fabrics with liquids.

15 This invention comprises a machine in which the fabrics being treated are placed in a perforated or open mesh receptacle capable of being moved vertically in a liquor container by the action of a plunger, the movement of which plunger first lowers the 20 perforated or open mesh receptacle into the liquor, then exerts a squeezing or pressing action on the fabric in the receptacle, then releases the pressure on the fabric and finally lifts the receptacle from the liquor.

25 The invention comprises further means for ensuring the circulation of the liquor through the fabrics during treatment and means for ridding the fabrics of a large proportion of the liquor which would otherwise be retained by them before their removal from the cage when the treatment in 30 that container is completed.

The invention will be described with reference to the accompanying drawings.

35 Fig. 1 is a transverse section of the machine.

Fig. 2 is an elevation from rear of machine.

Fig. 3 is a detail section of plunger clutch 40 mechanism.

Fig. 4 is a sectional plan of Fig. 3 on line 4-4.

Fig. 5 is a front elevation partly in section of machine adapted to be operated by 45 hand.

Fig. 6 is a transverse elevation partly in section of same.

The machine comprises a container A into which the washing or dyeing liquor is 50 placed. Inside the container A is a cage B containing the fabrics to be treated, the cage B being provided with perforations b in the bottom and sides to admit of the liquor in the container A entering therein. A plunger

C is given a reciprocating motion within 55 the cage from a crank shaft D driven by a continuously rotating pulley F:

The container A is formed with a movable bottom A¹ on to which the cage B rests when in the lower position. The bottom A¹ 60 consists of a series of laths a¹ carried on pivots a affixed to the sides of the container A. Each pivot a is connected to a rod A² by a link a² so that by moving the rod A² 65 the laths may be rotated into a vertical position thereby preventing the cage B from descending to the bottom of the container. When in this position a large proportion 70 of the liquor can be squeezed out of the fabrics in the cage and so retained in the container when the cage and fabrics are removed. A handle a³ outside the container A is provided on the rod A² for operating the laths a¹ with means for preventing the escape of the liquor round the outlet. 75

The perforated cage B is provided with a flange b¹ around its upper edge formed with lugs b² adapted to engage the arms B¹ 80 of a spider loosely carried on the rod C¹ of the plunger C; a bearing surface c mounted on the plunger C is arranged to come in contact with the central portion of the spider on the upward stroke of the plunger C whereby the spider and cage B are raised with the plunger C. Each of the 85 arms B¹ carries a roller b³ adapted to bear on the sides of the container A. A pin b⁴ is employed for locking the arms B¹ of the spider to the cage B during operation. The lugs b² are disengaged from the arms B¹ by 90 a partial rotation of the spider.

The plunger C is carried by a connecting rod C¹ C² pivoted to a lever D¹ fulcrumed on a stationary part of the machine. The lever D¹ receives an oscillating motion from 95 a crank shaft D through a connecting rod D². A balance weight W is mounted on the reverse end of the lever D¹ to that to which the plunger is connected. The connecting rod D² is pivoted to a bracket d slidable on the lever D¹ the position of the bracket d on the lever D¹ being adjusted by a screwed rod d¹ and hand wheel d² to vary the throw of the lever D¹. 100

The plunger rod C is formed in two parts 105 C¹ C², one part C² connected to the lever D¹ and the other C¹ to the plunger or disc C. The upper part C² consists of two links

which extend down for some distance alongside the lower part C¹ which carries a projection c adapted to engage two spring clips c² carried by the links C². A ring c³ is employed for varying the pressure between the projection c and the clips c².

Thus when the pressure of the plunger on the fabrics in the cage exceeds a predetermined amount the projection c moves out of engagement with the clips c² and the upper rod C² is free to complete its normal movement without moving the piston or disc C. When the upper rod C² moves upwards again, the projection c re-engages the clips c² and moves the plunger C up again to the upper end of the stroke. The plunger C is formed with a flap or other valve c³ arranged to open when the plunger is on its downward stroke to allow some of the liquor in the cage B to escape therethrough and so ensure circulation of the liquor in the container A.

One member E¹ of a dog or other clutch E is keyed on to the crank shaft D adapted to engage the second member E² which is mounted on a continuously driven pulley or gear wheel F loosely mounted on the shaft and bearing against a collar f pinned to the shaft. The member E¹ of the clutch E is disengaged from the member E² by a forked lever F¹ carried on the frame operated by a hand or foot lever. When the member E¹ has been disengaged from the member E² carried on the pulley F a bevel wheel F² mounted on the member E¹ is brought into engagement with a second bevel wheel F² carried on the frame and connected to a hand wheel f¹ by which the crank shaft D may be rotated to bring the plunger C to the top of its stroke in order that the fabrics or the cage B may be removed from the container A. A battery of containers may be worked simultaneously by providing additional cranks on the shaft D as shown by the dotted lines on Fig. 2.

The action of the machine is as follows:— When the crank D is at its highest position the cage B is resting on the bottom of the container A and the plunger or disc C has moved down inside the cage B exerting the required pressure on the fabrics therein to press out the liquor therefrom. As the crank D rotates, the plunger or disc C is raised from the fabrics in the cage leaving them loose, and when it reaches the spider bracket clipped to the top of the cage B its further movement raises the cage and its contents through the liquor, allowing the liquor to accumulate in the bottom of the container. As the crank D commences to ascend after reaching the bottom of the stroke, the cage B is lowered, through the liquor in the container A, and the mass of liquor at the bottom, owing to its own inertia and the relative smallness of the space between the sides

of the cage and the container, is forced through the perforations in the bottom of the cage thereby lifting all the fabrics and causing them to float about in the liquor. When the cage reaches the bottom of the container the piston or disc continues its downward movement and forces the fabrics through this fresh liquor in the cage, and finally squeezes or presses the liquid out of the fabrics, the cycle of operations then being repeated.

In the modification shown in Figs. 5 and 6, the machine is arranged for operation by hand or by foot. The liquor is contained in a container A and the fabrics to be treated placed in a net cage B carried by the plunger C. The lever D¹ is in this case prolonged to form the operating handle H and the connecting rod C³ is directly pivoted thereto and to the plunger C. A link h is also pivoted to the lever D¹ and a treadle H¹ provided so that the machine may be operated by foot. A wringing machine G of ordinary construction may be mounted above the container A on slides g so that it may be moved out of the way when not in use.

A machine constructed according to this invention gives the following advantages:—

A machine in which all the goods are in succession (1) squeezed (2) lifted through the liquor (3) allowed to float about in the liquor so as to obtain thorough saturation.

A machine in which the goods to be washed are kept in a container and moved about in the liquor without rotary or centrifugal action and without mechanical parts or projections moving about amongst them.

A machine in which an adjustable counterweight is used to balance the load and reduce the power needed to operate the machine.

A machine adapted to extract as much of the washing liquor as possible from the goods before they are removed from the machine.

The apparatus may be adapted for use with an ordinary domestic washing tub or portable copper when the frame would be mounted on a lid adapted to fit on the tub or copper and/or the plunger made spherical to give correct pressure in a spherical bottomed receptacle.

What I claim as my invention and desire to protect by Letters Patent is:—

1. In a machine for treating fabrics with liquid the combination with an outer container for the liquid of a plunger working therein, and a perforated or open mesh receptacle for the fabric moved up and down in the outer container by the action of the plunger, the movement of the plunger first lowering the fabric receptacle into the liquid, then exerting a squeezing action on the

fabric, then releasing the pressure on the fabric and finally lifting the fabric receptacle from the liquid.

2. In a machine for treating fabrics with liquid the combination with an outer container for the liquid of a receptacle for the fabrics to be treated, slideable vertically in the outer container, a plunger moving in the cage, means for reciprocating the plunger in the cage and container, means whereby the plunger will lift the cage when it reaches the top thereof and means whereby the downward movement of the plunger in the cage will be stopped when the pressure of the plunger on the articles therein has reached a predetermined value.

3. In a machine for treating fabrics with liquid the combination with an outer container for the liquid of a receptacle for the fabrics to be treated movable vertically in the outer container, a plunger moving in the container operated through a connecting rod from a lever pivoted to the frame of the

machine, a balance weight on the reverse end of the lever and links by which the lever is rocked.

4. In a machine for treating fabrics with liquid the combination with an outer container for the liquid of a receptacle for the fabrics to be treated, slideable vertically in the outer container, a plunger moving in the cage, means for reciprocating the plunger in the cage and container, means connected with a continuously rotating shaft for driving the plunger, and means for automatically disconnecting the plunger from said driving means when the pressure of the plunger on the fabric exceeds a predetermined amount.

In testimony whereof I have hereunto set my hand in presence of two subscribing witnesses.

WILLIAM STEPHEN COX GLOVER.
